The ornamental design for a confection, as shown and described.

DESCRIPTION

FIG. 1 is a front isometric view of a confection showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The greyscale shading shown in FIGS. 1–7 is provided solely for the purpose of showing surface contours. The dash-dot lines in the figures and the ghosted areas within the dash-dot lines show portions of the confection that form no part of the claimed design.
